UNITED STATES PATENT OFFICE.

JOHN B. WALKER, OF BIRMINGHAM, ALABAMA.

MOLDING APPARATUS.

1,156,449.

Specification of Letters Patent.

Patented Oct. 12, 1915.

Application filed March 31, 1915. Serial No. 18,281.

To all whom it may concern:

Be it known that I, JOHN B. WALKER, a citizen of the United States, residing at Birmingham, in the county of Jefferson and State of Alabama, have invented certain new and useful Improvements in Molding Apparatus, of which the following is a specification.

My invention relates to improvements for casting open hearth charging boxes and like large hollow articles.

The main object of my invention is to cheapen the cost of casting articles of this character by simplifying the operations with a view to obtaining a more rapid production and also to design the apparatus to produce a casting that will be of uniform firmness of metal and free from irregular shape and cracks.

My preferred means for obtaining the ends in view, comprises a metallic arbor composed of a plurality of separate parts that are loosely mounted upon the drag and connected to means for spreading them to receive the sand and form the core and for collapsing or releasing them to collapse together both from the sides and ends of the drag to provide for the shrinkage of the casting from all directions.

My invention also involves certain improvements in the construction of the drag which has stop lugs to center the expanded arbor thereon and in the means for adjusting, locking and releasing the plungers which control the adjustments of the arbor sections.

My invention also involves the several other features of construction and arrangements of parts which are hereinafter claimed, and which in their preferred embodiment are more particularly described by reference to the accompanying drawings which form a part of this specification, and in which:—

Figure 1 is a plan view showing the drag and the sectional arbor in expanded position ready for the formation of the sand core. Fig. 2 is a partial side elevation and partial sectional view showing the apparatus assembled for casting. Figs. 3, 4 and 5 are detail views of an arbor section; and Fig. 6 is a vertical sectional view taken on the line $x-x$ of Fig. 2.

Similar reference numerals refer to similar parts throughout the drawings.

The apparatus consists briefly of a drag 1

having mounted thereon an arbor formed in four parts which are respectively numbered 2, 3, 4 and 5. The parts 2 and 3 are similar except that they are reversely disposed and they are similar to the parts 4 and 5, except that the latter have at one end a downwardly inclined wall 6, as will be seen in dotted lines Fig. 4, which is a view typical of the several arbor segments. These segments are formed of castings having perforated side, top and end walls and reinforcing intermediate vertical ribs 7 and an internal horizontal flange 8 near the bottom. The ribs 7 extend from the top where they are widest to the flange 8 and to this flange 8 of each section I hinge a pair of toggle links 9, the inner ends of which are pivoted to bosses on a plunger 10. A plunger is provided to control the arbor sections 2 and 3 and it extends to the right through a notch in the low marginal wall 11 which surrounds the drag. The outer end of the plunger 10 is provided with an upturned wedge shoulder 12 which is adapted to receive a wedge 13 inserted between it and the wall 11 so as to force the plunger to the right and expand the toggle links 9 to move the sections 2 and 3 outwardly and endwise into their expanded position. The arbor sections 4 and 5 are similarly constructed and connected to a plunger 10 which projects beyond the left hand end of the drag and is similarly connected thereto by a wedge 13. The drag is provided with a series of lugs 14 which are placed to be engaged by the sides and ends of the expanded arbor sections so as to properly center the latter upon the drag.

In order to prevent the sand working in between the arbor sections, I provide a number of narrow metal plates which will cover the spaces between the arbor sections without interfering with their free collapsing movement. The end openings are closed by vertical plates 15. The top longitudinal opening between each pair of sections is closed by a longitudinal top plate 16 and the transverse opening between the two pairs of sections is closed by a curved plate 17 which fits over the top and down the sides of the arbor. The marginal wall 11 extends all the way about the drag and its inner face 18 is beveled as seen in Fig. 6. The object of the plungers 10 being to control the position of the arbor sections, the first operation is to expand the arbor sections by forcing their plungers outwardly. This is done by

driving in the wedges 13 between the end of the drag and the shoulders 12 and causing the toggle links 9 to spread the arbor sections until they are held rigidly against the 5 end and side lugs 14. After the several joint plates have been placed in position, a wooden core box (not shown) is placed over the arbor on the drag and held in position by fitting snugly in the recess formed by the 10 beveled faces 18 of the marginal wall 11 thereof. Green molding sand is then rammed into this space between the arbor and the core box to form the lower part of the sand core. The upper portion of the core is 15 then formed by ramming sand over the top of the arbor and resting a sweep held vertically on the top of the wooden core box and drawing it from end to end thereof. One end of the box desired to be cast by this 20 apparatus has slots with holes in it and this end is formed by a separate sand core 19 which is set in its proper place on the drag (see Fig. 2). After the core has been rammed and the core box removed and the 25 end core 19 placed, a chill 20 is then placed over the cores and the apparatus is ready for pouring. The chill 20 is preferably formed of cast iron and is held in place on the drag by pins 21 so placed that they will 30 engage in holes 22 in the drag and center the core properly on the drag. The chill is provided on top with a hole 23 for pouring spout and riser and a hole 24 for watching the flow of metal when pouring. It is also 35 provided with handles 25 by means of which it can be readily lifted on and off the drag. After the casting has been poured the chill is quickly removed before the casting has cooled beyond the surface heating of the 40 metal. The wedges 13 are then quickly knocked out freeing the plungers 10 and allowing the core to contract from all directions, thus accommodating the shrinkage of the casting and preventing the opening of 45 the sand. By removing the chill and exposing the casting to the air it is allowed to cool evenly which produces a casting of regular form and uniform firmness of metal. Although it is desirable to use a cast iron 50 chill I do not want to limit my apparatus to its use as any standard type of cope can be readily substituted and utilized to a good advantage in its place. For venting purposes and to facilitate the removal of the 55 core sand, I provide the bottom of the drag with a pair of centrally disposed rectangular openings 26 which are covered by the arbor sections in their expanded position. The side walls of the arbor are perforated 60 so that the core will vent itself freely thereunder and through the bottom of the drag.

The salient feature of my invention is the grouping of independent sets of core arbor sections for control by independent plungers, thus permitting the greatest flexibility

of adjustment to take care of the shrinkage in the casting.

What I claim as new and desire to secure by Letters Patent, is:—

1. In a molding apparatus, the combination with a drag, of a sectional core arbor mounted thereon, a plurality of plungers, means actuated by each plunger to adjust an independent group of arbor sections, and means to releasably hold the plungers in 75 predetermined position relative to the drag, substantially as described.

2. In a molding apparatus, the combination with a drag, of a sectional core arbor mounted thereon, a plurality of oppositely 80 and laterally movable plungers, means to operably connect a different group of arbor sections to each plunger, and devices to releasably hold the plungers and arbor sections in predetermined position relative to 85 the drag, substantially as described.

3. In a molding apparatus, the combination with a drag, of a sectional core arbor mounted thereon, a plurality of laterally 90 movable plungers, an independent operating mechanism actuated by each plunger and connected to a group of arbor sections, and keys to releasably hold the plungers and arbor sections in predetermined position relative to the drag, substantially as de- 95 scribed.

4. In a molding apparatus, a drag, a core arbor formed in two pairs of relatively adjustable sections, means on the drag to limit the expanding movements of the arbor sections, and an independently movable actuating means for adjusting each pair of arbor sections, substantially as described.

5. In a molding apparatus, the combination with a drag having side and end stop 105 lugs, of a core arbor seated centrally on the drag and divided along vertical planes into a plurality of relatively movable sections, a plurality of plungers controlling said sections, and releasable means which actuate 110 the plungers to expand and hold the arbor sections against said stop lugs, substantially as described.

6. In a molding apparatus, the combination with a cope and a drag having side and 115 end stop lugs, of a core arbor loosely mounted on the drag and divided vertically into a plurality of relatively movable sections, a plurality of laterally movable plungers controlling said section, releasable means to actuate the plungers and expand the arbor sections against said stop lugs, and means to cover the joints between the expanded arbor section without interfering with their collapsing movements, substan- 120 tially as described.

7. In a molding apparatus, a drag having a low marginal wall and a series of side and end stop lugs in its bottom, a core arbor formed of a plurality of independently ad- 130

- justable sections which are loosely mounted between said lugs on the drag, plunger controlled means to expand the sections of each set until they engage said lugs, said means comprising a plunger which projects beyond the marginal wall of the drag, and releasable means to adjust and hold the plunger in "arbor-expanded" position, substantially as described.
- 10 8. In a molding apparatus of the character described, a core arbor divided longitudinally and transversely into sections, plungers, links connecting a number of sections to each plunger, wedge means to adjust each plunger on the drag to expand the arbor sections connected thereto, and means to limit the expanding movements of the arbor sections to center them on the drag, substantially as described.
- 15 9. In a molding apparatus, a drag, a core arbor loosely mounted on the drag, said arbor being open at its bottom and being parted along vertical transverse and longitudinal planes, independent laterally movable means to control the expansion of the arbor, and means to cover the arbor joints without interfering with their collapsing movements.
- 20 10. In a molding apparatus, a drag, a cope, a core arbor slidably mounted on the drag and divided along vertical transverse and longitudinal planes into sections, means to move the sections apart endwise and laterally, means to limit the endwise and lateral expanding movements of the sections, and external wedges which engage said means and hold the sections expanded, said sections being adapted when released to contract both from endwise and lateral directions.
- 25 11. A core arbor divided along vertical and longitudinal planes into sections, longitudinal and transverse cover plates for the top and vertical side joints of the arbor and which rest loosely against the adjacent edges of the sections, and means to expand the sections apart laterally in both endwise and lateral directions.
- 30 12. A hollow troughlike core arbor formed of sections, each section having a side, a top and an outer end wall, plunger means to move said sections relatively to separate them, releasable means to hold the sections expanded, and joint protecting means to prevent the core sand packing in the open joints of the expanded sections and interfering with their free collapse.
- 35 13. A hollow expandible core arbor formed by hollow sections comprising each an outer end wall, a top wall, and an outer side wall, laterally movable plungers, links connecting each plunger to adjacent opposite arbor sections, and releasable means to force the plungers in opposite directions to expand the sections both laterally and endwise, substantially as described.
- 40 14. The combination with a flat drag having a marginal side wall, of a hollow expandible core arbor formed by hollow sections comprising each an outer end wall, a top wall, and an outer side wall, said sections being loosely mounted to slide on the drag, an internal horizontal flange in each section, horizontal plungers which project laterally from within the core arbor beyond said drag wall, links connecting each plunger to the flanges of opposite adjacent arbor sections, wedge means to force the plungers in opposite directions and expand the sections respectively connected thereto both laterally and endwise, and stop means on the drag to center the expanded arbor thereon, there being bottom venting openings in the drag.
- 45 15. In combination, a drag having a marginal wall with a tapered inner mold centering face and end openings therethrough, plungers projecting through said end openings and slidale on the bottom of the drag, a sectional core arbor mounted on the drag and having generally the shape of an inverted trough, toggle links connecting opposing sections of the arbor to each plunger, end and side stop lugs on the drag to limit the expanding movements of the arbor and center it on the drag, joint protecting means for the arbor sections, wedges adapted to be inserted between the drag and the plunger ends to force the plungers outwardly and expand the arbor, a cope, and means to center the cope on the drag, substantially as described.
- 50 16. In testimony whereof I affix my signature in presence of a witness.
- JOHN B. WALKER.
